UNITED STATES PATENT OFFICE.

CLARENCE M. CREWS, OF BROOKLYN, NEW YORK, ASSIGNOR TO UNDERWOOD TYPE-WRITER COMPANY, OF NEW YORK, N. Y., A CORPORATION OF DELAWARE.

TYPEWRITING MACHINE.

Application filed November 3, 1923. Serial No. 2,429.

To all whom it may concern:

Be it known that I, CLARENCE M. CREWS, a citizen of the United States, residing in Brooklyn Borough, in the county of Kings, city and State of New York, have invented certain new and useful Improvements in Typewriting Machines, of which the following is a specification.

This invention relates to manifolding upon superposed plies of work-webs in typewriting machines. For example, the improvements are adapted for doing continuous billing work, and also for performing, upon continuous work-webs, other classes of manifold work, especially where the number of carbon copies required for successive writings varies.

One of the objects is to adapt standard front-strike typewriting machines to perform web manifolding by simpler means and more easily than heretofore.

Relatively short carbon-sheets are interleaved with the continuous work-webs, to enable a form which is usually printed on the webs to be typed and manifolded. A relative shifting between the set of carbon-sheets and the web-plies is effected in a novel manner after the typing of every form. The arrangement of the web in the typewriting machine is novel. Instead of following the usual manner of introducing the webs around the platen and up in front thereof to be typed upon, the method is followed, according to this invention, of introducing the pack of web-plies with the interleaved carbons forwardly over the top of the platen and down in front thereof and backwardly beneath the same. The downward and backward movement of the web brings the same to position to receive the first line of type-impressions. Thereupon the usual feed-rolls (released during the insertion of the web) are caused to clamp the web upon the bottom of the platen, and the typing of the leading form proceeds line by line. It will be understood that the typing begins with the bottom form on the web, instead of with the leading or top form as heretofore. When the typing of the form is completed, the pack of webs and carbons is advanced around the platen until the pack is free of the platen, whereupon the

webs are shifted relatively to the carbons, while the carbons (still free of the platen) are held against movement with the webs. 55 This leaves the typed form at the bottom of the webs clear of the carbons, while the carbons are then in position for the manifolding of the next form above. At this juncture, the typed form or forms are severed from the web, this being conveniently done by means of a knife, which is placed in a suitable position at the front of the platen.

Then the bottom end of the web with 65 the carbons is inserted downwardly and backwardly around the platen until the fresh form thereon is in position to receive the first line of typing, whereupon the cycle of operations is repeated. 70

From the front of the platen rises an introductory paper-table of considerable height, and over this table the large number of continuous work-webs (preferably as many as can be typed at a single writing) 75 is thrust or introduced bottom end first down to the front of the platen, and thence around under the platen to the rear. The webs (which may be either loose or fan-folded) may have forms printed upon them 80 or they may be blank according to the nature of the work, and they may be fed from any suitable source of supply at the rear of the machine, such as web-reels or a set of individual web-packs. One of the differences over the prior art is that the webs are inserted in the machine bottom end first, so that the form at the top of the web is the last one to be typed. 85

The interleaving carbons are carried by 90 a carbon-carrier, preferably of flexible sheet material, which is guided down to the front of the platen by the front paper-table, and may be conveniently fed around the platen with the work-webs. The carbons are attached at their upper ends to the carbon-carrier by means of carbon-holding strips or blades. The blades are superposed on the carrier, so that the carbon-carrier and hence the supporting front introductory table will not be required to extend to an unnecessary height above the platen. 95 100

In the initial writing position of the first form or stretch of the work-webs, the major

portions of the flexible carbon-carrier, the carbons and the forms to be typed extend around the platen to the rear thereof. As the typing proceeds, the work is line-fed in the usual manner, and the flexible carbon-carrier, which lies between the work-webs and the platen, is line-fed with the work. The carbon-carrier, while sufficiently flexible to be fed around the platen, is nevertheless stiff enough to feed the carbon-blades away from the platen at the line-spacing operation, and thus keep the carbons straight and unwrinkled.

When the typing on the bottom form section is completed, the platen is turned forward by one of the usual platen-turning knobs to feed the work-webs and carbon-carrier to a carbon-shifting position. In the carbon-shifting position, cutouts in the carbon-carrier, situated just below the free lower ends of the carbons, register with openings in the front paper-table, and the carbons are straight and free of the platen.

Carbon-stripping auxiliary feed-rolls are arranged to coast through said openings and cutouts are then moved from ineffective to effective position to grip the lower margins of the work-webs through the cutouts in the carbon-carrier and through the openings in the paper-table. The platen feed-rolls are at the same time cast off. The auxiliary feed-rolls are then rotated by a finger-piece while the carbon-carrier is held stationary to feed the work-webs one form length in anti-line-feed direction and relatively to the carbons. The lower ends of the work-webs pass from the front to the rear of the flexible carbon-carrier through a slit in the carrier located just below the cutouts, and as they are fed by the carbon-stripping rolls they pass along the rear of the carbon-carrier down to the platen and around beneath the platen from front to rear. It will be seen that the lower end of the carbon-carrier serves as a front-insertion guide for the work-webs to direct the webs to and around beneath the platen.

When the shifting of the work-webs relatively to the carbons has been accomplished, the completed web-section is severed by a draw knife that is slidably mounted on the back of the front paper-table and that projects through a slot in the paper-table to the front thereof. The knife is located just below the openings in the front paper-table, and is a short distance below the slit in the carbon-carrier at this stage of the operation, so that it can sever the webs between the carbon-carrier and the paper-table. The knife is sharp pointed so that it will be sure to separate all of the webs from the back of the flexible carbon-carrier and sever them.

When the typed web-sections have been

severed, the auxiliary feed-rolls may be cast off and the platen feed-rolls may be made effective. After this has been done the number of webs to be used in typing the next form or communication may be determined by withdrawing the lower margins of any surplus webs from the slit in the flexible carbon-carrier, turning them with the interleaved carbons up and back, and clipping them in an inactive position by means of a clip on the carbon-carrier at the upper end thereof. When it is desired to increase the number of webs in active use this may be done by withdrawing as many inactive webs from the clip as are required and inserting their lower margins through the slit in the carbon-carrier.

Should it be desired to substitute a letter-head or other facing sheet for one of the work-webs to receive the original impressions, this may be done just after a completed set of forms has been cut off, by retaining in active use as many webs and carbons as the number of carbon copies desired, and by superposing the letter-head upon the outermost active carbon with its lower margin extending down through the slit in the carbon-carrier. The knife may be moved to a gaging position to serve as a lower edge gage for the letter-head in this operation, if desired.

When the re-arrangement of the webs, if required, has been effected, the carbon-holder together with the webs is fed around the platen in an anti-line-feed direction to locate the fresh forms around the platen in first writing line position. In this operation, the carbon-carrier again acts as a front-insertion guide for the work-webs. The reverse feeding of the carbon-carrier and the work-pack to writing position may be effected by rotation of the platen knobs, but preferably it is accomplished by seizing the end of the carbon-carrier projecting beyond the rear of the platen, together with the severed web-sections which are still in the machine, and pulling the carbon-carrier to the rear. The web-sections are thus withdrawn from the machine by this same operation in the grip of the operator, and may be disposed of in an orderly manner. The work is now in position for a repetition of the cycle with reference to the fresh web-sections.

An important advantage of the present invention is the elimination of creeping of loose plies or webs with relation to each other, which creeping heretofore has been a source of difficulty in typing upon separate continuous work-webs. The amount that the webs are fed around the platen in anti-line-feed direction to locate them in first writing line position, is equal to the amount that they are subsequently fed forward.

The creeping in one direction may be counteracted by the creeping in the opposite direction for each form therefore, and hence no creeping needs to accumulate. It will be 5 recognized, of course, that no creeping results from the feeding of the work-webs by the auxiliary rolls.

It is a further feature of the invention that there is no retardation of the work-webs in line-feeding due to the inertia of 10 the webs or of the reels upon which the webs are sometimes carried. At the line-feeding operation, the platen has to feed forward only the carbon-carrier and the 15 form-section which is being typed, and the inertia of these is very slight.

In accordance with one feature of the invention, provision is made for rendering the auxiliary feed-rolls effective by the same 20 operation that renders the platen feed-rolls ineffective, and for rendering the auxiliary feed-rolls ineffective by the same operation that renders the platen feed-rolls effective. This not only saves the time of the operator 25 but also assures that the work-webs will always be moved squarely with relation to the platen.

A further feature of the invention relates to the construction of the carbon-holding 30 blades and to their mounting on the flexible carbon-carrier. The blades are superposed upon studs on the carbon-carrier and are clamped thereon, for example, by nuts, threaded onto the studs. The carbons have 35 loops on their upper ends which receive the blades. The blades have means to engage the ends of these loops to mechanically locate and retain the carbons in correct position longitudinally of the blades.

40 When it is desired to change the width of the webs in use, the operator feeds the flexible carbon-carrier forward completely out of the machine and inserts another carbon-carrier having webs of the desired width interleaved with its carbons. 45 The carbon-carriers are all of the same width, so that they may be guided by side walls on the front paper-table, but the widths of the carbons carried by them may 50 correspond to the widths of the interleaved work-webs. To introduce a fresh carbon-carrier into the machine, a piece of heavy paper or cardboard is fed around the platen from the rear to be used as a front-insertion 55 guide for the carbon-carrier, and is afterward withdrawn.

No claim is made in this case to features disclosed in co-pending application 674,839, filed November 15, 1923, which shows and 60 broadly claims web-severing mechanism of the type herein illustrated.

Other features and advantages will hereinafter appear.

In the accompanying drawings, 65 Figure 1 is a sectional side elevation of a

part of an Underwood Standard correspondence typewriter machine, having the improvements of the present invention applied thereto; the parts being shown in writing position. 70

Figure 2 is an enlarged fragmentary detail sectional view of the flexible carbon-carrier, showing how the work-webs are led from the front to the rear thereof through the slit. 75

Figure 3 is a front elevation, partly broken away, of the part of the machine shown in Figure 1.

Figure 4 is a fragmentary horizontal sectional detail view, showing the mounting of 80 the knife on the front paper-table, and its normal relation to the flexible carbon-carrier and to the work-webs.

Figure 5 is a fragmentary horizontal sectional view, showing the carbon-blades and 85 clip on the carbon-carrier.

Figure 6 is a fragmentary front elevation of the front paper-table, showing the openings through which the auxiliary feed-rolls act and the slot through which the knife 90 acts to sever the webs.

Figure 7 is a sectional side elevation, showing the parts in the positions occupied preparatory to feeding the webs with relation to the carbons. 95

Figure 8 is a fragmentary view similar to Figure 7, but showing the main feed-rolls cast off, and the auxiliary feed-rolls made effective, the mechanism for controlling the feed-rolls being also illustrated in this view. 100

Figure 9 is a view similar to Figure 7, showing the work-webs shifted with relation to the carbons, and ready for web-severing.

Figure 10 is a view similar to Figure 7, 105 showing the work-webs and carbon-holder drawn down to writing position after the completed sections have been severed.

The Underwood Standard correspondence typewriting machine comprises a platen 10 revolvably mounted by means of a platen-axle 11 in the ends 13 of a platen-frame 12. The platen-frame includes, besides end members, a rear paper-shelf 14 and a paper-apron 15 extending forward from the 110 paper-shelf, around the lower side of the platen 10 and conforming to the contour thereof. Feed-rolls 16 carried by bell-cranks 17 pivoted on a shaft 18 are urged toward the platen 10 by springs 19. These feed-rolls 16 are arranged to be cast off by depression of a finger-piece 20 which is connected through a rock-shaft 21, crank 22, link 23 and crank 24 to rock a cam-shaft 25 which engages the tails of the bell-cranks 17 to rock them to ineffective position. Brackets 26 are mounted by means of screws 27 on the ends 13 of the platen-frame 12, and these brackets 26 are connected to each other by a cross-bar 28 on which is mounted 115 120 125 130

a front paper-table 29, whereon the work-webs are presented to the machine, and from time to time straightened out for the carbon-stripping operation. Continuous sheets or 5 work-webs A are conducted, bottom end first, over the curved upper end 30 of the paper-table 29 and down across its face to the platen 10 at the front thereof. The work-table 29 has fixed side walls 31 forming guides for a long sheet 32 of cardboard, celluloid or other flexible material, which serves as a carrier and backing for carbons 33 and at intervals is employed as a front-insertion guide for the work-webs A, as will 10 be explained later. The carbon-carrier 32 has threaded studs 34 at opposite sides of its upper end on which carbon-holding blades 35 are mounted in superposed relation. Each blade 35 may be supported by both 15 of the studs 34, when loose work-plies are used. Nuts 36 threaded on the studs 34 hold the carbon-blades 35. Each carbon-sheet 33 has a loop at its upper end in which a carbon-blade, when detached from the 20 carrier 32, may be inserted. The carbon-blades 35 are cut away slightly between the ends, as shown in Figure 3 to form shoulders 37 for engaging the ends of the carbon-sheet loops to mechanically locate and 25 detain the carbons 33 in the desired location longitudinally of the blades. The end portions 38 of the blades 35 are made thicker than the middle portions 39 thereof, the thicker end portions 38 serving to space the 30 middle portions 39 from each other to afford clearance for the carbons and work-webs. The carbons 33 with the interleaved work-webs A extend downward from said blades 35 together. The carbons 33 terminate just above cutouts 40 which are provided in the carbon-carrier or backing sheet 32 for a purpose to be explained later, but the work-webs A extend across these 40 cutouts 40 and may be passed from the front to the rear of the backing or carbon-carrier 32, through a slit 41 formed therein at the lower extremity of the cutouts, whereby the backing may catch the work-sheets 45 and draw them around the platen. At the beginning of typing a form or communication, the parts are in substantially the positions indicated in Figure 10. The active portions of the work-webs A with the carbons 33 interleaved extend around the platen 10 outside the carbon-carrier 32 and terminate a short distance beyond the slit 41 in the carbon-carrier. As the typing 50 proceeds the platen is line-spaced in the usual way, and this feeds the work-web A and the flexible carbon-carrier 32 forward together.

When the typing of the section has been completed the platen is rotated forward by means of either of the platen-turning knobs 42 (one of which is shown) to locate the

work in a carbon-shifting position at the front of the platen where the carbons 33 and webs can extend in a straightened-out condition, and to locate the cutouts 40 of the carbon-carrier in register with openings 70 43 formed in the front paper-table 29. In this position the lower ends of the carbons lie just above the cutouts 40 and openings 43, but the lower ends of the work-webs A extend down across the cutouts and openings 75 and between auxiliary feed-rolls 44 and 45, which may now be made effective to grip and feed the work-webs A down or in an anti-line-feed direction, while the carbon-carrier 32 with its carbons 33 is held 80 stationary. The actuating rolls 44, whereby motion is imparted to the work-webs A, project through the openings 43 and are mounted on a shaft 46 journaled in the brackets 26. The shaft 46 has a knob 47 85 90 95 100 105 110 115 120 125 130 fast on its end and this knob is provided with a small crank-handle 48. The arrangement is such that the shaft may be turned by operating either the knob 47 or the crank-handle 48, the crank-handle being preferable for turning the rolls 44 quickly through a great distance, and the knob being preferable for finely adjusting the position of the sheets.

A rock-shaft 49 journaled in the brackets 95 100 105 110 115 120 125 130 26 has crank arms 50 fast upon it which carry at their outer ends a shaft 51 that bears the pressure rolls 45 for co-operating with the actuating feed-rolls 44. A spring 52 connected to one of the arms 50 and to a bracket 53 fixed on the front paper-table 29 urges the rolls 45 toward the rolls 44. Means are provided for controlling the pressure rolls from the finger-piece 20, the arrangement being such that the pressure rolls 45 are automatically rendered effective when the finger-piece is moved to cast off the platen feed-rolls 16 and the pressure rolls 45 are automatically rendered ineffective when the finger-piece is moved to restore the platen feed-rolls 16. For this purpose, the rock-shaft 49 is provided with a crank arm 54 which is connected through a link 55 to a crank 56 fast on the rock-shaft 21. In the normal position of the finger-piece 20, as seen in Figure 2, the link 55 is drawn down by the crank 56 to hold the pressure rolls 45 released. It will be observed that the link 55 is on a dead center with relation to the rock-shaft 21 and crank 56 in this position of the parts, and hence the spring 52 will be powerless upon the feed-rolls 45. As soon as the finger-piece 20 is depressed, however, the link 55 is raised and the feed-rolls 45 are moved to effective position under the urging of the spring 52. It will be noticed that provision is made for lost motion between the link 55 and crank 54, the connection between these members being effected through a slot 57 in the link 130

55 and a pin 58 on the crank 54. Should it be desired to adjust the work-webs A after they have been inserted around the platen 10 to writing position, this lost-motion connection enables the operator to take hold of the pressure rolls 45 and swing them to ineffective position, while the finger-piece 20 is depressed to hold the platen feed-rolls 16 ineffective.

10 When the typing of the end section or set of forms has been completed and the work has been advanced to carbon-shifting position, as seen in Figure 7, the operator depresses the finger-piece 20 to cast off the 15 platen feed-rolls 16 to make the auxiliary feed-rolls 44, 45 effective (see Figure 8). He then holds the carbon-carrier 32 stationary with his left hand, while rotating the auxiliary feed-rolls 44 rapidly with his 20 right hand by turning the crank-handle 48. He thus strips the carbons from the work-webs and locates the work-webs A in web-severing position, as seen in Figure 9. The 25 web-severing position of the webs A with relation to the carbon-carrier 32 may be indicated by suitable gage marks (not shown) on the carbon-carrier and on the work-webs, and the carbon-shifting position of the carbon-carrier may also be determined by reference to suitable gage marks (not shown) on the front paper-table 29 and on the carbon-carrier.

When the webs A are in severing position, the upper edge of the completed form-section coincides with a slot 59 in the paper-table 29 through which a double-edged draw-knife 60 extends, and along which the knife may be drawn in either direction to sever the webs. The knife 60 is carried by a 40 block 61 slidably mounted in a channel bar 62 secured to the rear face of the paper-table 29, and is moved from side to side of the table by a handle 63. The knife 60 normally occupies a position beyond the 45 bounds of the work-webs A, but behind the carbon-carrier 32. The blade is sharp pointed to assure the separation of all of the webs A from the rear of the carbon-carrier, thereby to assure their severance by the 50 knife. To further assure this result, the operator may press the carbon-carrier 32 toward the knife 60. The front paper-table has a tongue 65 extending down between the openings 43 through which the auxiliary feed-rolls 44, 45 act, and this tongue 55 serves to prevent the lower ends of the work-webs A from catching on the bar 62 when the webs are next fed in an anti-line-feed direction.

60 When the webs A have been severed, the finger-piece 20 is actuated to restore the platen feed-roll 16 to effective position and to cast off the auxiliary feed-rolls 45. The number of work-webs A in active use may

now be changed to cause a different number of carbon copies to be made of the next communication typed, by withdrawing any surplus webs A¹ from the slit 41 in the carbon-carrier 32 and turning them, with their carbons 33, up and back and clipping them 70 in a clip 66 on the carbon-carrier. This clip comprises a stationary jaw 67 mounted on one of the threaded studs 34 and a swinging jaw 68 pivoted on an ear 69 on the carbon-carrier and urged toward the stationary 75 jaw 67 by a leaf-spring 70 which bears against a cam 71 on the movable jaw. Should it be necessary to increase the number of webs A in active use instead of diminish the number, the necessary webs may 80 be withdrawn from the clip 66 and their lower ends may be readily inserted through the slit 41 in the carbon-carrier 32.

The lower end 72 of the carbon-carrier 85 32 extends around the platen and far enough to the rear thereof to enable the operator to seize the end 72 and draw the carbon-carrier together with the carbons 32 and work-webs A from web severing to writing position. The typed and severed web-sections are removed from the platen by this 90 operation. The work is now in the position shown in Figure 10, which is substantially the first writing line position. The entire cycle of operations described may 95 now be repeated with reference to the new web-section.

Variations may be resorted to within the scope of the invention, and portions of the improvements may be used without others. 100

Having thus described my invention, I claim:

1. In a typewriting machine, the combination with a revoluble platen, of a carbon-carrier sufficiently flexible to be fed around the platen with the work-webs and carbons, and arranged to be shifted in line-feed direction relatively to the work-webs to strip the carbons from the typed form-sections. 110

2. A typewriting machine having means, including a revoluble line-spacing platen, for typing upon superposed work-webs, means presenting the work-webs to the machine bottom end first at the delivery side of the platen, with carbons interleaved, and means for holding the carbons stationary while the work-webs are carried in an anti-line-feed direction to strip the interleaved carbons from the typed sections and present them to fresh work-web sections. 115

3. In a typewriting machine, the combination with a platen, of means extending over the platen from the rear, for presenting and guiding superposed work-webs, bottom end first, to the platen downwardly at the front thereof and rearwardly under the platen, and means at the delivery side 120

- of the platen for holding carbons interleaved with the work-webs.
4. In a typewriting machine, the combination with a platen, of means for guiding superposed work-webs to the platen for typing, and a carbon-carrier to hold carbons interleaved with the work-webs, and shiftable in line-feed direction relatively to the work-webs to strip the carbons from the typed work-web sections.
5. In a typewriting machine for typing upon superposed continuous work-webs fed to the machine bottom end first at the front of the platen, the combination of a revoluble platen, and a carbon-carrier having carbons attached to the upper end thereof, said carbons lying in front of the carbon-carrier, the carbon-carrier being sufficiently flexible to be fed around the platen with the work-webs and carbons, and having a slit below the lower ends of the carbons through which the work-webs may pass to the rear of the carbon-carrier, so that the carbon-carrier may serve as a front-insertion guide for the work-webs and interleaved carbons.
6. In a typewriting machine for typing upon superposed continuous work-webs fed to the machine bottom end first at the front of the platen, the combination of a revoluble platen, and a carbon-carrier having carbons attached to the upper end thereof, said carbons lying in front of the carbon-carrier, the carbon-carrier being sufficiently flexible to be fed around the platen with the work-webs and carbons, and having a slit below the lower ends of the carbons through which the work-webs may pass to the rear of the carbon-carrier, so that the carbon-carrier may serve as a front-insertion guide for the work-webs and interleaved carbons, and the carbon-carrier being long enough to extend around and to the rear of the platen when the work-webs are free of the platen at the front thereof, so that the carbon-carrier may be gripped by the operator and pulled to the rear to draw the work-webs down to writing position.
7. A carbon-sheet carrier for holding carbon-sheets interleaved with successive sections of continuous work-webs, comprising carbon-attaching means at its upper end, a backing-portion over which the carbons and interleaved work-webs extend, and a front-insertion guide-portion for guiding the lower ends of the work-webs to and around the platen from the front to the rear thereof, the backing and front-insertion guide portions being sufficiently flexible to be fed around the platen, and the carbon-carrier having cutouts at the lower end of the backing-portion below the lower extremities of the carbons, through which the work-webs may be gripped and fed relatively to the carbons, and a slit at the lower

extremities of the cutouts, through which the work-webs pass from the front of the backing-portion to the rear of the front-insertion portion.

8. A typewriting machine having means, including a revoluble line-spacing platen, for typing upon superposed continuous work-webs, and having means for presenting and introducing the webs, bottom end first, to the platen and downwardly at the front thereof, a set of bodily movable carbon-holders at the delivery side of the platen, each having a carbon-sheet depending from it toward the platen, and means for feeding the carbon-holders bodily away from the platen as the platen is line-spaced to keep the carbons unwrinkled.

9. In a typewriting machine for typing upon superposed continuous work-webs introduced bottom end first to the machine at the front of the platen, a revoluble platen, and a carbon-carrier sufficiently flexible to be fed around the platen with the work-webs, the carbon-carrier being advanceable out of the machine at the will of the operator, to permit the substitution of another carbon-carrier having work-webs of a different kind interleaved with its carbons.

10. A carbon-carrier for typewriting machines, comprising a base, a pair of studs at opposite sides of the base, and a carbon-blade impaled at its opposite ends on the studs, the carbon-blade being cut away intermediate its ends to form shoulders for mechanically locating a looped carbon-sheet threaded onto the blade in correct position longitudinally of the blade, and for detaining the carbon-sheet in such position.

11. In a typewriting machine, in combination, a revoluble platen, and a carbon-carrier at the delivery side of the platen to hold carbons interleaved with the bottom end portion of continuous work-webs introduced bottom end first to the platen at the front thereof, the carbon-carrier being arranged for movement away from the platen during typing.

12. In a typewriting machine for typing upon continuous work-webs introduced bottom end first to the platen at the front thereof, in combination, a revoluble platen, a carbon-carrier at the delivery side of the platen to hold carbons interleaved with the bottom end portions of the work-webs, and means to render ineffective any selected number of the work-webs.

13. In a typewriting machine, in combination, a revoluble platen, a carbon-carrier arranged to hold carbons interleaved with work-webs introduced to the platen bottom end first at the front thereof, the carbon-carrier being advanceable with the work-webs during typing, and being arranged to be held stationary during shifting of the

- work-webs relatively thereto, and a front paper-table for guiding the work-webs and the carbon-carrier to the front of the platen, the front paper-table having side walls to 5 guide the carbon-carrier and to maintain it square with the platen during the relative shift of the work-webs and carbons.
14. In a typewriting machine, in combination, a revolute platen, a carbon-carrier at 10 the delivery side of the platen and arranged to hold carbons interleaved with the bottom end portions of work-webs introduced to the platen bottom end first at the front thereof, and means for guiding the carbon-carrier in 15 a path at right angles to the platen, and for preventing skewing of the carbon-carrier during carbon-shifting.
15. In a typewriting machine, in combination, a revolute platen, a set of individual 20 carbon-holders at the delivery side of the platen for holding carbons interleaved with the bottom end portions of work-webs introduced to the platen bottom end first at the front thereof, means for feeding the carbon-holders from the platen with the work, and 25 guides for causing said holders to move at right angles to the platen.
16. In a typewriting machine, in combination, a revolute platen, a carbon-carrier at 30 the delivery side of the platen arranged to hold carbons interleaved with the bottom end portions of work-webs introduced to the platen bottom end first at the front thereof, and means for engaging the sides 35 of the carbon-carrier and guiding it in a path at right angles to the platen, the carbon-carrier being advanceable out of the machine at the will of the operator, to permit another carbon-carrier of the same 40 width, but having work-webs of a different width interleaved with its carbons, to be substituted in the machine.
17. In a typewriting machine, a revolute platen, a carbon-carrier for holding carbons 45 interleaved with continuous work-webs, the carbon-carrier being advanceable with the work-webs to a carbon-shifting position at the front of the platen, and means for feeding the work-webs relatively to the carbons.
- 50 18. In a typewriting machine, a revolute platen, a carbon-carrier for holding carbons interleaved with continuous work-webs, a front paper-table over which the carbon-carrier travels, the paper-table having openings 55 in its face, and carbon-stripping rolls arranged to co-operate through the openings to feed the work-webs relatively to the carbons, the carbon-carrier having cutouts through which the carbon-stripping rolls 60 coact, and the carbon-carrier being advanceable with the work-webs to a carbon-stripping position wherein the cutouts in the carbon-carrier registers with the openings in the front paper-table.
- 65 19. In a typewriting machine, a revolute platen, a carbon-carrier for holding carbons interleaved with continuous work-webs, means for guiding the carbon-carrier toward and from the platen, the carbon-carrier having cutouts beyond the field of the carbons, and carbon-stripping rolls arranged to coact through the cutouts to shift the work-webs relatively to the carbons when the carbon-carrier is moved to position the cutouts between the carbon-stripping rolls. 70
20. In a typewriting machine, a revolute platen, a carbon-carrier for holding carbons interleaved with continuous work-webs, means for guiding the carbon-carrier toward and from the platen, the carbon-carrier having cutouts beyond the field of the carbons, normally ineffective carbon-stripping rolls at front and rear of the work-webs and of the carbon-carrier, and 75 means for rendering the carbon-stripping rolls effective when the carbon-carrier is located with the cutouts between the carbon-stripping rolls, to enable the work-webs to be shifted relatively to the carbons by operation of carbon-stripping rolls. 80
21. In a typewriting machine for typing upon a plurality of superposed webs introduced to the machine bottom end first at the front of the platen, the combination with a revolute platen and line-spacing mechanism therefor, of a carbon-stripping device including a bodily retractable carbon-carrier at the front of the platen, and means for retracting the work-webs while the carbon-carrier is held stationary, to present the carbons to fresh sections of the work-webs, 85 said carbon-carrier having a bodily line-feeding movement at the line-feeding operation of the platen. 90
22. In a typewriting machine for typing upon a plurality of superposed webs introduced to the machine bottom end first at the front of the platen, the combination with a revolute platen, of a carbon-carrier having bodily line-spacing movements at the front of the machine, and means for relatively shifting the carbon-carrier and the work-webs to interleave the carbons with fresh sections at the bottom end portions of the webs. 100
23. In a typewriting machine, the combination with a revolute platen, of a front paper-table having openings therein, feed-rolls arranged to co-operate through the openings, a carbon-carrier mounted for movement along the paper-table toward and from the platen, the carbon-carrier being sufficiently flexible to be fed around the platen with the work, and having openings beyond the field of its carbons arranged to be moved into register with the openings in the front paper-table to enable the feed-rolls to shift the work-webs relatively to the carbons to a web-severing position, and a knife at the lower ends of the openings in 110
- 120
- 125
- 130

the front paper-table for severing the typed web-sections when they have been shifted to severing position.

24. In a typewriting machine, in combination, a revoluble platen, a front paper-table having openings therein, feed-rolls arranged to co-operate through the openings, a carbon-carrier mounted for movement along the paper-table toward and from the platen, and sufficiently flexible to be fed around the platen with the work, the carbon-carrier having openings beyond the field of its carbons arranged to be moved into register with the openings in the front paper-table to enable the feed-rolls to shift the work-webs relatively to the carbons to a web-severing position, and a knife above the platen and at the front thereof, for severing the typed web-sections when they have been shifted to severing position, the carbon-carrier having a slit located a short distance above the knife in the severing position, through which the lower ends of the work-webs pass, and the carbon-carrier being long enough to extend down around the platen when in the severing position; the arrangement being such that the carbon-carrier serves as a front-insertion guide to draw and direct the shorn webs to the front of the platen and around the platen from the front to the rear thereof.

25. In a typewriting machine, in combination, a revoluble platen, carbon-holders for holding carbons interleaved with continuous work-webs introduced to the machine bottom end first at the front of the platen, the carbon-holders being advanceable to position the carbons free of the platen and in a straight condition to permit relative work-web and carbon shifting, a knife at the front of the platen for severing the typed web-sections from the remainder of the webs when the carbons have been stripped from the typed sections, and means for directing the shorn ends of the webs to the front of the platen and around the platen from the front to the rear thereof.

26. In a typewriting machine, in combination, a revoluble platen, a carbon-carrier for holding carbons interleaved with continuous work-webs introduced to the machine bottom end first at the front of the platen, the carbon-carrier being advanceable to position the carbons free of the platen and in a straight condition to permit relative work-web and carbon shifting, a knife at the front of the platen to sever the typed web-sections from the remainder of the webs and thereby to leave the carbons and the untyped work-webs free of the platen so that any desired number of the webs and carbons may be turned up and back to an inactive position, and means for securing such webs and carbons in inactive position.

27. In a typewriting machine, in combination, a revoluble platen, a carbon-carrier for holding carbons interleaved with continuous work-webs introduced to the machine bottom end first at the front of the platen, the carbon-carrier being advanceable to position the carbons free of the platen to permit relative work-web and carbon shifting, a knife normally located beyond the bounds of the work-webs but behind the carbon-carrier, the knife having a sharp-pointed blade to separate the work-webs from the back of the carbon-carrier, and means for drawing the knife across the webs to sever the typed sections after the carbons have been stripped therefrom.

28. In a typewriting machine, a platen, means at the delivery side of the platen for holding carbons interleaved with the lower ends of continuous work-webs introduced bottom end first into the machine at the front thereof, a lower edge gage for engaging and mechanically positioning a separate work-sheet in predetermined relation to the continuous work-webs and outside of the work-webs, to receive the original type-impressions while such impressions are duplicated through the carbons upon the continuous work-webs.

29. In a typewriting machine, a platen, means at the delivery side of the platen for holding carbons interleaved with the bottom end portions of continuous work-webs introduced bottom end first into the machine at the front thereof, and a gage for positioning a separate sheet in predetermined relation to the continuous work-webs for typing at the same operation therewith.

30. In a typewriting machine, in combination, a revoluble platen, a carbon-carrier for holding carbons interleaved with continuous work-webs introduced into the machine bottom end first at the front of the platen, a carbon-carrier having cutouts just below the lower ends of its carbons, a front paper-table along which the carbon-carrier travels, the table having openings therein, feed-rolls arranged to co-operate through the openings, the carbon-carrier being advanceable to a carbon-shifting position wherein the cutouts in the carbon-carrier register with the openings in the paper-table so that the feed-rolls may contact through the cutouts and the openings to shift the work-webs relatively to the carbons, the carbon-carrier having a slit at the lower extremities of the cutouts, through which the work-webs pass from the front to the rear of the carbon-carrier, and the front paper-table having a slot a short distance below the slit in the carbon-carrier when the latter is in carbon-shifting position, and a knife operating in said slot to sever the typed web-sections, the lower end

of the carbon-carrier extending down to and around the platen in the carbon-shifting and web-severing position of the carbon-carrier to serve as a front-insertion guide 5 for the shorn ends of the work-webs to direct the next untyped web-sections to writing position.

31. In a typewriting machine, the combination with a revoluble platen and feed-10 rolls co-operating therewith, of means for holding carbons interleaved with superposed continuous work-webs, auxiliary feeding means at the front of the platen for feeding the work-webs relatively to the 15 carbons, and additional auxiliary feeding means for feeding the work-webs and carbons together to writing position.

32. In a typewriting machine for typing upon a plurality of superposed work-webs 20 introduced into the machine bottom end first at the front of the platen, carbon-interleaving means at the front of the machine, means for relatively shifting the carbons and work-webs, means for severing the completed work-web sections at the front of 25 the machine, and a front-insertion guide for the work-webs and carbons.

33. An attachment for typewriting machines to adapt them to do manifold work 30 upon continuous work-webs, comprising brackets arranged to be detachably secured upon the platen-frame of a machine, a front paper-table on the brackets having a curved upper end for guiding the work-webs 35 smoothly from the rear of the paper-table onto its face, the paper-table also having side walls to guide a carbon-carrier, having work-webs interleaved with its carbons, toward and from the platen at the front 40 thereof, feed-rolls mounted on the table to coat through openings therein to shift the typed web-sections clear of the carbons, and a knife on the table for severing the typed web-sections.

34. An attachment for typewriting machines to adapt them to do manifold work upon continuous work-webs, comprising a front table, means for connecting the front table to the platen-frame of a typewriting 50 machine, means on the front table for guiding a carbon-carrier having its carbons interleaved with the work-webs, feed-rolls mounted on the table and coacting therethrough to shift the work-webs relatively 55 to the carbons, and a knife on said table for serving the typed work-web sections after they have been shifted clear of the carbons, the knife being so positioned that the web-sections interleaved with the carbons will be free to be turned back to an 60 inactive position after the typed sections have been severed, to vary the number of webs in active use.

35. In a typewriting machine, in combination, a revoluble platen, a carbon-car-

rier at the front of the platen for holding carbons interleaved with work-webs introduced bottom end first into the machine at the front thereof, a front introductory table over which the carbon-carrier travels, 70 the carbon-carrier being advanceable to a carbon-shifting position, carbon-stripping rolls for feeding the work-webs relatively to the carbons in such position, a knife for severing the typed-section when they have 75 been stripped of the carbons, the front paper-table having openings through which the carbon-stripping rolls coat, a slot at the lower ends of the openings along which the knife slides, and a tongue extending 80 down between the openings to the slot to keep the shorn ends of the work-webs on the face of the paper-table and prevent their catching on the lower end of the slot.

36. In a typewriting machine, in combination, a revoluble platen, main feed-rolls co-operating with the platen, auxiliary feed-rolls above the platen, and common means for controlling the main and auxiliary feed-rolls, arranged to render them alternately 90 effective.

37. In a typewriting machine, in combination, a revoluble platen, main feed-rolls co-operating with the platen, auxiliary feed-rolls above the platen at the front thereof, 95 a finger-piece arranged for operation to cast off and restore the main feed-rolls, and connections between the finger-piece and the auxiliary feed-rolls to make the auxiliary feed-rolls effective when the main feed-rolls are cast off, and to make the auxiliary feed-rolls ineffective when the main feed-rolls are restored.

38. In a typewriting machine, in combination, a revoluble platen, main feed-rolls co-operating with the platen, auxiliary feed-rolls above the platen at the front thereof, a finger-piece arranged for operation to cast off and restore the main feed-rolls, and connections between the finger-piece and the auxiliary feed-rolls to make the auxiliary feed-rolls effective when the main feed-rolls are cast off, and to make the auxiliary feed-rolls ineffective when the main feed-rolls are restored, said connections having provision for lost motion to enable the auxiliary feed-rolls to be moved to ineffective position while the main feed-rolls are cast off.

39. In a typewriting machine, in combination, a revoluble platen, main feed-rolls co-operating with the platen, auxiliary feed-rolls independent of the platen, a spring urging the auxiliary feed-rolls to effective 120 position, controlling means for casting off 125 and restoring the main feed-rolls, and connections from the controlling means to the auxiliary feed-rolls to render the auxiliary feed-rolls effective when the main feed-rolls are cast off, and to render the auxiliary feed-rolls ineffective when the main feed-rolls 130

are restored, said connections comprising a crank and a link, the arrangement being such that the crank and link are in a dead-center position when the main feed-rolls are effective so that the spring will be powerless to move the auxiliary feed-rolls to effective position.

40. In a typewriting machine, in combination, a revoluble platen, a carbon-carrier for holding carbons interleaved with continuous work-webs led around the platen, main feed-rolls co-operating with the platen to feed the work-webs and the carbons, auxiliary feed-rolls to feed the work-webs relatively to the carbons to accomplish a relative shift of the work-webs and carbons, and means for concomitantly casting off the main feed-rolls and making the auxiliary feed-rolls effective.

41. In a typewriting machine, in combination, a revoluble platen, a carbon-carrier for holding carbons interleaved with continuous work-webs led around the platen bottom end first from the front to the rear thereof, main feed-rolls co-operating with the platen to feed the work-webs and the carbons, the carbon-carrier being movable to a carbon-shifting position wherein the work-web and carbons are free of the platen, auxiliary feed-rolls for feeding the work-webs independently of the carbons down to and around the platen, and means for concomitantly casting off the main feed-rolls and making the auxiliary feed-rolls effective.

42. In a typewriting machine, in combination, a revoluble platen, a carbon-carrier for holding carbons inter-leaved with continuous work-webs led around the platen bottom end first from the front to the rear thereof, means for feeding the work-webs, the carbon-carrier and carbons to a carbon-shifting position with the carbons and work-webs free of the platen, means for guiding the work-webs down to and around the platen, feed-rolls independent of the platen for feeding the work-webs down to and around the platen independently of the carbons to accomplish a relative shift of the work-webs and carbons, means for concomitantly making the feed-rolls effective and providing clearance between the work-web guide and the platen for the passage of the work-webs, a knife for severing the typed web-sections after such relative shifting of the webs and carbons, and means for drawing the carbon-carrier, the carbons and the work-webs down to typing position around the platen.

43. In a web-typing machine having a revoluble platen and a platen-frame, a work-presenting table erected upon said platen-frame at the delivery side of the platen, over which a composite web is presented downwardly bottom end first at the front of the platen, for introduction downwardly

and rearwardly under the same, preparatory to typing the bottom form thereon.

44. In a web-typing machine having a revoluble platen and a platen-frame, a work-presenting table erected upon said platen-frame at the delivery side of the platen, over which a composite web is presented downwardly bottom end first at the front of the platen, means being provided in front of and under the platen for conducting the web downwardly and rearwardly under the platen, preparatory to typing the bottom form thereon.

45. In a web-typing machine having a revoluble platen and a platen-frame, a work-presenting table erected upon said platen-frame at the delivery side of the platen, over which a composite web is presented downwardly bottom end first at the front of the platen, means being provided in front of and under the platen for conducting the web downwardly and rearwardly under the platen, preparatory to typing the bottom form thereon, a carbon-carrier at the delivery side of the platen, the work-webs being threaded through said carbon-carrier, and means at the delivery side of the platen for effecting a relative carbon-stripping movement between the carbon-carrier and the web-plies.

46. In a web-typing machine having a revoluble platen and a platen-frame, a work-presenting table erected upon said platen-frame at the delivery side of the platen, over which a composite web is presented downwardly bottom end first at the front of the platen, means being provided in front of and under the platen for conducting the web downwardly and rearwardly under the platen, preparatory to typing the bottom form thereon, a carbon-carrier at the delivery side of the platen, the work-webs being threaded through said carbon-carrier, and means at the delivery side of the platen for effecting a relative carbon-stripping movement between the carbon-carrier and the web-plies, said carbon-carrier mounted for movement upon said table towards and away from the platen.

47. In a web-typing machine having a revoluble platen and a platen-frame, a work-presenting table erected upon said platen-frame at the delivery side of the platen, over which a composite web is presented downwardly bottom end first at the front of the platen, means being provided in front of and under the platen for conducting the web downwardly and rearwardly under the platen, preparatory to typing the bottom form thereon, a carbon-carrier at the delivery side of the platen, the work-webs being threaded through said carbon-carrier, means at the delivery side of the platen for effecting a relative carbon-stripping movement between the carbon-carrier and the

web-plies, and a web-severing knife at the delivery side of the platen at the lower end portion of said table.

48. A typewriting machine having means, 5 including a revoluble line-spacing platen, for typing upon superposed continuous work-webs, and having means for presenting and introducing the webs over the top of the platen and bottom end first down to 10 the platen at the front thereof, a set of bodily movable carbon-holders at the delivery side of the platen, each having a carbon-sheet depending from it toward the platen, means for feeding the carbon-holders bodily 15 away from the platen as the platen is line-spaced, to keep the carbons unwrinkled, and means for stripping the carbons from the bottom section of the work-web.

49. In a front-strike typewriting machine, 20 the combination with a revoluble platen, of means mounted at the delivery side of said platen for presenting a work-web bottom end foremost to the front of said platen, and means at the delivery side 25 of said platen for holding interleaved carbons stationary by their top ends while the work-web is pulled forwardly to strip the carbons from the typed sections and present them to 30 fresh sections.

50. In a front-strike typewriting ma-

chine, the combination with a revoluble platen, of means mounted at the delivery side of said platen for presenting a work-web bottom end foremost to the front of 35 said platen, means at the delivery side of said platen for holding interleaved carbons stationary by their top ends while the work-web is pulled forwardly to strip the carbons from the typed sections and present them to 40 fresh sections, and means for subsequently severing the typed sections from the web.

51. In a front-strike typewriting machine, 45 the combination with a revoluble platen, of means mounted at the delivery side of said platen for presenting a work-web bottom end foremost to the front of said platen, means at the delivery side of 50 said platen for holding interleaved carbons stationary by their top ends while the work-web is pulled forwardly to strip the carbons from the typed sections and present them to 55 fresh sections, and means for subsequently severing the typed sections from the web, means being provided for introducing and guiding the bottom of the web downwardly and rearwardly with the interleaved carbons, preparatory to typing the bottom form thereon.

CLARENCE M. CREWS.
